UNITED STATES PATENT OFFICE.

GEORGE S. AUER, OF CLEVELAND, OHIO.

FLOOR-REGISTER.

1,255,848.

Specification of Letters Patent. Patented Feb. 12, 1918.

Application filed February 7, 1917. Serial No. 147,078.

To all whom it may concern:

Be it known that I, GEORGE S. AUER, a citizen of the United States, residing at Cleveland, in the county of Cuyahoga and State of Ohio, have invented certain new and useful Improvements in Floor-Registers, of which the following is a specification.

My invention relates to improvements in floor registers used in connection with hot air flues or conduits of hot air furnaces.

The primary object of the invention is to provide a generally improved floor register of this class of exceedingly simple, cheap, and efficient construction having an improved form of register-face and border-frame as well as providing improved means for mounting and supporting the same.

A further object is to provide improved means for mounting and securing the register fan housing or casing to the register-face.

A still further object is the provision of an improved register-face and border-frame having similarly beveled and under-channeled marginal portions, said under-channeled marginal portion of the border-frame being adapted to receive and contain the floor engaging flange of the register box about the register receiving opening of the floor so that the outer beveled portion of the border-frame will be supported on the floor independently of the floor engaging flange of the register box or casing and forming a close and substantially uniform frictional fit with the floor.

A still further object is the provision of an improved register-face adapted to be used either with or without a border-frame and having a similarly formed channeled portion on its under side for a similar purpose when used without a border-frame.

With the above mentioned and other ends in view, the invention consists in the novel construction, arrangement, and combination of parts, hereinafter described, illustrated in one of its embodiments in the accompanying drawings, and more particularly pointed out in the appended claims.

Referring to the drawings, forming a part of this specification Figure 1, is an isometric view of a corner portion of the improved floor register in its operative position for use, the register fans being removed for the purpose of clearer illustration of the parts.

Fig. 2, an enlarged sectional view through the margin of the improved register-face

showing the manner of using the same without the register box or fan casing to the corner portions of the register-face.

Similar numerals of reference designate like parts throughout all the figures of the drawings.

The improved floor register comprises a border-frame 1, a register-face 2, and a register fan housing or casing 3, the latter being secured to and carried by the register-face 2, within the register box 4, connected to and communicating with the hot air flue or conduit.

The register face 2, is formed of a suitable and convenient open pattern to form a grille 2^a, and the border-frame is provided with a marginal channeled portion 1^a, on its under side to receive and contain the floor engaging flange 4^a, of the register box 4. As a means for providing for the support of the border-frame directly upon the flooring 5, independently of the flange 4^a, as well as providing for a close neat fit between the outer edges of the border-frame 1, and the floor, said border-frame is provided about its outer periphery with a depending floor engaging friction bearing flange 1^b, the outer edge or periphery being preferably beveled as shown at 1^c.

The border-frame is provided about its inner periphery with an inset register-face receiving and supporting portion 1^d, preferably provided with a plurality or series of register-face supporting and leveling studs 1^e. These studs 1^e, are adapted to take under and support the marginal portions of the register-face 2, and the tops may be ground off to level the register-face or give it a proper fit with respect to the border-frame 1. It will be seen that the register-face receiving and supporting portion 1^d, is also provided with an inset seat portion 1^f, to receive and surround the register-face 2, and the outer periphery of the register-face 2, is provided with a beveled or inclined portion 2^b, corresponding to and harmonizing with the beveled portion 1^c, of the border frame.

As a means for adapting the register-face 2, to be used without a border-frame as shown in Fig. 2, said register-face is provided with a marginal channeled portion 2^c, having, as shown, the same function as that of the channeled portion 1^a, of the border-frame, and also having a depending

floor engaging friction bearing flange or rib 2^a, similar in function to the flange or rib 1^b, of the border-frame 1.

As a means of securing the register box 4, 5 to the register-face 2, the latter is provided at its corners with attaching lugs 2^c, (one corner portion only being shown) adapted to receive and contain screw bolts 6, (see Fig. 2) extending through the inwardly extending flanged portions 3^a, of the fan housing, said bolts being vertically disposed within the corner portions of the fan housing or casing and provided with nuts 6, as shown most clearly in Fig. 2, of the drawings. This method of attachment not only 15 enables the fan housing or casing to be readily attached to or detached from the register-face but enables the housing or casing to be readily drawn up or adjusted by 20 simply turning the threaded heads of the bolts 6, by a screw driver, or other appropriate instrument from the top of the register-face.

From the foregoing description, taken in 25 connection with the accompanying drawings, the operation and advantages of my invention will be readily understood.

Copies of this patent may be obtained for five cents each, by addressing the "Commissioner of Patents, Washington, D. C."

Having thus described one of the embodiments of my invention, what I claim and desire to secure by Letters Patent, is,—

1. A floor register, comprising a beveled under-channeled border-frame, and a similarly beveled and under-channeled register-face.

2. A floor register, comprising a border-frame having a marginal channel on its under side and an inset register-face receiving extension adapted to support a register-face.

3. A floor register, comprising a beveled border-frame having a marginal channel on its underside and an inset register-face receiving extension about its inner periphery, and a register-face having a similarly beveled and channeled marginal portion seated on said extension and surrounded by said border-frame.

In testimony whereof I have affixed my signature in the presence of two witnesses.

GEORGE S. AUER.
